RAIN CAPE

Vernon D. Griffith and John Bruns, Wichita, Kans.,
assignors of one-half to Fred E. Bonner and Ben
Bonner, jointly, both of Wichita, Kans.

Filed Oct. 16, 1961, Ser. No. 67,078

Term of patent 3½ years

(Cl. D3—3)

Fig. 1.

Fig. 2.

Fig. 3.

FIG. 1 is a front elevational view of the rain cape,
showing our new design;

FIG. 2 is an elevational view of one side thereof;

FIG. 3 is a rear elevational view thereof;

FIG. 4 is a top plan view thereof; and

FIG. 5 is a front perspective view of the rain cape as
is appears in a wearing position.

The dominant features of our design reside in the
combination with the pull over rain cape disclosed of the
specific integral, hood structure formed with the back
and having a half round head covering on the front
thereof together with draw strings at the neck, all as
shown.

We claim:

The ornamental design for a rain cape, as shown and
described.
